DOOR LATCH INCLUDING A PERMANENT MAGNET AND A LATCHING ELECTROMAGNET
Kurt Remhof, Schalksmühle, Germany, assignor to Albrecht Jung elektrotechnische Fabrik, Schalksmühle, Germany

Filed Apr. 8, 1965, Ser. No. 446,747

Claims priority, application Germany, Apr. 9, 1964, J 12,582; Apr. 11, 1964, J 25,640
7 Claims. (Cl. 292—201)

This invention is concerned with latching mechanisms, and more particularly with such mechanisms for use on doors such as, for instance, doors of dwellings, or cabinet or closet doors.

It is one object of this invention to provide new and improved latching mechanisms for the aforementioned description.

Another object of this invention is to provide integral dual action latching mechanisms capable of holding a door closed by the magnetic attraction of a permanent magnet and an armature for the latter, and also capable of locking a door by positive action.

Another object of this invention is to provide a dual action latching mechanism of the aforementioned description including parts operative to perform either of both of the two functions of the composite device.

Another object of this invention is to provide a dual action latching mechanism of the aforementioned description involving a minimum of bulk, being adapted to be operated remotely by an electromagnet, or solenoid, requiring a minimum of bulk, and the constituent parts of which are positioned in such a way that they can be accommodated in a small substantially prismatic housing having approximately the thickness of that of a door.

Another object of this invention is to provide a latching mechanism of the aforementioned description which does not exceed the dimensions of a conventional lock that would be used for locking the particular kind of door for which the latching mechanism is intended.

Still another object of this invention is to provide a latching mechanism of the aforementioned description having a considerable mechanical strength, yet having space requirements not exceeding a prismatic space having a height of about 2.6 inches, a width of about 2 inches and a thickness of about 1 inch.

Other objects of the invention and advantages thereof will be better understood from the following description and the accompanying drawings showing two preferred embodiments of the invention, and wherein;

FIG. 1 is a front elevation of a cabinet made of wood and having a plurality of compartments each closed by an individual door, FIG. 1 showing one of the compartments as being associated with a latching mechanism embodying the present invention;

FIG. 2 is a side elevation of that portion of the latching mechanism of FIG. 1 which is built into the cabinet body of FIG. 1;

FIG. 3 is a side elevation of the portion of the latching mechanism of FIG. 1 which is built into the door of the structure of FIG. 1 rather than into the cabinet body thereof;

FIG. 4 is a front view of the structure of FIG. 2;

FIG. 5 is a front view of that portion of a latching mechanism embodying this invention intended for use on sliding doors rather than on hinged doors which is intended to be fastened to the sliding doors;

FIG. 6 is a side elevation of the structure of FIG. 5;

FIG. 7 is a side elevation of that portion of the latching mechanism for sliding doors intended to be fastened to the fixed frame of the door and to cooperate with the portion of the structure illustrated in FIGS. 5 and 6;

FIG. 8 is a section of the structure shown in FIGS. 5

2

and 6 showing on a considerably larger scale the parts which are arranged inside of the structure of FIGS. 5 and 6, FIG. 8 being taken along 8—8 of FIG. 9; and

FIG. 9 is a side elevation of the structure of FIGS. 5 and 6 as seen when separating the two constituent shells of that structure.

Referring now to the drawings, and more particularly to FIGS. 1—4 thereof, reference numeral 1 has been applied to generally indicate a cabinet having six compartments 2. Each of the six compartments 2 may be closed by a door 3. The latch mechanism for each door 3 comprises two cooperating units generally designated by the reference characters L₁, L₂. Unit L₁ is secured by means of wood screws 6 to the corner formed by horizontal board 4 and vertical board 5. Unit L₂ is secured by wood screws 9 to the corner of one of the doors 3 which is juxtaposed in the closed position of that door to the corner formed by boards 4 and 5.

Unit L₁ comprises two complementary shells 10, 11 arranged in abutting relation (see FIG. 4) and jointly forming a housing enclosing a substantially prismatic space. Housing 10, 11 has a pair of relatively wide parallel outer surfaces positioned at right angles to the plane of the paper on which FIGS. 1 and 4 are drawn. Housing 10, 11 further comprises a pair of relatively narrow outer surfaces positioned at right angles to the aforementioned relatively wide outer surfaces. One of said relatively narrow surfaces defines a pair of superimposed passageways 17 and 17a, each between the space enclosed by shells 10, 11 and the exterior thereof. A pair of hollow rivets 12 project transversely through the relatively wide surfaces of housing 10, 11, integrating its constituent shells 10, 11 into a structural unit. Each of the two hollow rivets 12 defines a cylindrical duct having a sufficiently large inner diameter to allow the passage of wood screws 6 through the aforementioned relatively wide outer surfaces of housing 10, 11. Wood screws 6 extend beyond housing 10, 11 and secure the latter to the vertical board 5 of cabinet 1. Reference numeral 13 has been applied to

40 indicate a permanent bar magnet arranged inside the prismatic space defined by shells 10 and 11. Permanent bar magnet 13 projects with one end thereof into passageway 17 and has a pole surface 13a substantially flush with the relatively narrow outer end surface of housing 10, 11

45 shown to the right of FIG. 2. Fixed armature plate 8 secured by wood screws 9 to door 3 cooperates with permanent magnet 13 in keeping door 3 closed, when closed. This is effected by magnetic attraction between permanent magnet 13 and armature plate 8. Armature plate 8 forms a support for a hook-shaped latch 7 projecting from the surface of armature plate 8 and forming jointly with armature plate 8 the latch unit which has been generally designated by the reference character L₂. Movable latch 16 inside of housing 10, 11 is intended to cooperate with

50 latch 7 when it is desired to maintain the door 3 locked by positive means rather than merely closed by magnetic attraction of parts 8 and 13. Latch 7 is arranged on door 3 in juxtaposition to passageway 17a defined by housing 10, 11 and enters into housing 10, 11 whenever door 3 is closed and then engages latch 16. Latch 16 forms an integral part of a pivotable armature 15 under the action of an electromagnet 14 arranged inside housing 10, 11. The armature latch unit 15, 16 rests against a pair of abutments or stops 18 and 19.

55 FIG. 2 shows the electromagnet in de-energized condition when its armature 15 is not attracted to the upper position thereof. In the lower position of armature 15 latch 16 may engage latch 7 and thus maintain the cabinet door 3 locked. The pull exerted upon latch 16 by one who tries to forcibly open locked cabinet door 3 is received by stop or abutment 19, and thus not transmitted to the fulcrum of armature 15 which is likely to be dam-

60 65 70 75 80 85 90 95

FIG. 2 shows the electromagnet in de-energized condition when its armature 15 is not attracted to the upper position thereof. In the lower position of armature 15 latch 16 may engage latch 7 and thus maintain the cabinet door 3 locked. The pull exerted upon latch 16 by one who tries to forcibly open locked cabinet door 3 is received by stop or abutment 19, and thus not transmitted to the fulcrum of armature 15 which is likely to be dam-

aged if subjected to such pull action. Upon energization of electromagnet or solenoid 14 armature 15 is lifted and latch 16 moved out of engagement with latch 7, thus making it possible to open door 3 against the magnetic action of parts 13 and 8.

It will be apparent from the foregoing that part 8 performs two functions, i.e. it forms an armature cooperating with permanent magnet 17 to maintain door 3 closed by forces of magnetic attraction between these two parts, and it forms also a support for latch 7 cooperating with latch 16.

Referring now to FIGS. 5 to 9, reference character L1' has been applied to generally indicate an assembly unit intended to be secured to a sliding door (not shown) and reference character L2' has been applied to generally indicate an assembly unit intended to be secured to a fixed door frame 5' for the sliding door. Assembly unit L1' includes a housing made up of two complementary shells 10', 11' which define a pair of enclosed spaces 20' and 21'. Housing 10', 11' has a pair of parallel, relatively wide outer surfaces of which one is its front surface shown in FIG. 6, and the other its rear surface. Housing 10', 11' further comprises a pair of relatively narrow lateral surfaces at right angles to the aforementioned pair of relatively wide surfaces. As best shown in FIG. 5 one of these relatively narrow surfaces defines a pair of superimposed passageways 17' and 17a'. Passageway 17' arranged at a higher level than passageway 17a' interconnects the space or compartment 20' inside of housing 10', 11' with the exterior of said housing, and passageway 17a' interconnects the space or compartment 21' inside of housing 10', 11' with the outside of said housing. A pair of hollow rivets 12' project transversely through the relatively wide surfaces of housing 10', 11' and integrate its two constituent shells 10' and 11' into a structural unit. Each hollow rivet 12' defines a cylindrical duct for the passage of screws 6' intended to secure housing 10', 11' to a sliding door. These screws have been deleted in FIGS. 5 and 8. They are arranged in exactly the same fashion as the wood screws 6 shown in FIGS. 2 and 4 and their cross-section is shown in FIGS. 6 and 9. Reference character 22' has been applied in FIG. 9 to indicate transverse passageways in each of shells 10' and 11' into which the aforementioned hollow rivets 12' are inserted. A permanent bar magnet 13' is arranged in space or compartment 20' of housing 10', 11'. Bar magnet 13' is provided with a coaxial stem 23' projecting into a recess 24' defined by shells 10' and 11'. Mounted on stem 23' is a screw nut 25' resting with one surface thereof against one of the lateral walls of recess 24'. Rotation of screw nut 25' on screw-threaded stem 23' makes it possible to precisely position bar magnet 13' relative to housing 10', 11'. As shown in FIG. 9 bar magnet 13' projects with the right end thereof into passageway 17' and has a pole surface 13a' arranged substantially flush with the narrow outer surface of housing 10', 11' shown to right of FIG. 9. Reference numeral 8' has been applied to indicate a rectangular armature plate attracted by permanent bar magnet 13' and thus tending to oppose separation of units L1' and L2'. Armature plate 8' is arranged substantially parallel to the pole surface 13a' of bar magnet 13'. Armature plate 8' supports hooked latch 7' at a point thereof juxtaposed to, and arranged at the same level as, passageway 17a' of housing 10', 11'. If housing 10', 11' is moved toward armature plate 8' the latch 7' thereof enters into passageway 17a' and cooperates with a latch 16' inside housing 10', 11'. Latch 16' is pivotally mounted on a pin 26' and under the action of a helical over-center spring 27' of which one end is attached to latch 16' and the other end is attached to a fixed frame structure for an electromagnet 14'. Pin 26' is supported by a U-shaped bracket 40' riveted to shell 10' at 28'. Latch 16' defines a pair of recesses 29' and 30' each situated to opposite sides of the fulcrum of latch 16' formed by pin 26'. Latch 16' 75

has two limit positions of which one, i.e. the lower, is shown in FIG. 8, and which is characterized by the fact that the longitudinal axis of over-center spring 27' is situated below of pivot or fulcrum 26'. If the front end, or right end, of latch 16' is lifted or pivoted in counterclockwise direction against the action of spring 27', the longitudinal axis of spring 27' is moved across and past pivot or fulcrum 26', and then over-center spring 30' biases latch 26' in counterclockwise direction to the upper limit position thereof. As long as latch 16' is in its lower limit position over-center spring 27' biases latch 16' in clockwise direction. The aforementioned electromagnet 14' is provided to move latch 16' selectively to each of its two aforementioned limit positions. To this end electromagnet 14' is provided with a klapper-type armature 15' pivoted at 31' and under the bias of a helical spring 32'. One end 33' of spring 32' is secured to housing 10', 11', while the other end 34' of spring 32' is secured to a substantially Z-shaped abutment 35' integral with armature 15'. It is apparent from FIG. 9 that the space or compartment 21' of housing 10', 11', accommodates electromagnet 14', its armature 15', abutment 35' integral with the latter, latch 16' and the over-center spring 27' thereof. Compartment or space 21' further accommodates a pair of terminal clamps 36' and 37' for connecting electromagnet 14' into an electric energizing circuit.

In FIG. 9 latch 16' has been shown in the latching position thereof, its cooperating latch 7' having been indicated in that figure by a dash-and-dot line. In this position of latch 16' the units L1' and L2' cannot be separated, i.e. the sliding door cannot be opened. Upon energization of electromagnet 14' armature 15' is pivoted about its pivot or fulcrum 31' in counterclockwise direction, as seen in FIG. 9. As a result, the upper end of abutment 35' engages recess 30' in latch 16' and pivots latch 16' in counterclockwise direction to its upper limit position, or unlatched position (not shown). Now units L1' and L2' can readily be separated by overcoming the magnetic attraction between parts 13' and 8'. The sliding door will, however, not open unintentionally upon movement of latch 16' to its upper limit position, or unlatched position, on account of the action of permanent magnet 13' and its armature 8'. In the de-energized state of electromagnet 14' armature 15' rests against a stop 38' integral with housing 10', 11'. Upon re-energization of electromagnet 14' the abutment 35' of armature 15' engages the recess 29' in latch 16' and thus pivots latch 16' in clockwise direction as seen in FIG. 9, thus moving latch 16' to its lower limit position, or latching position.

While there has been described what is at present considered to be the preferred embodiments of the invention, it will be obvious to those skilled in the art that various changes and modifications may be made without departing from the invention, and it is, therefore, aimed in the appended claims to cover all such changes and modifications as fall within the true spirit of the invention.

What is claimed is:

1. A latching mechanism for doors comprising in combination:
  - (a) a housing including a pair of complementary shells defining an enclosed space, said housing having a pair of juxtaposed wide surfaces and having a narrow surface defining a pair of superimposed passageways between said space and the outside thereof;
  - (b) a permanent magnet inside said space projecting with one end thereof into one of said pair of passageways and having a pole surface arranged substantially flush with said narrow surface of said housing;
  - (c) a latch pivotally mounted inside said space and pivotable to an operative position and to a non-operative position, said latch having a latching surface arranged substantially in registry with the other of said pair of passageways;

- (d) an electromagnet inside said space including an armature for operating said latch; and
  - (e) a pair of hollow rivets projecting transversely through said juxtaposed surfaces of said housing and integrating said pair of shells into a structural unit, each of said pair of hollow rivets defining a cylindrical duct having a sufficiently large inner diameter to allow the passage of screws for supporting said housing through said juxtaposed surfaces of said housing.
2. A latching mechanism for doors comprising in combination:
- (a) a housing including a pair of complementary shells defining an enclosed space, said housing having a pair of parallel relatively wide outer surfaces and having a pair of relatively narrow outer surfaces arranged at right angles to said pair of relatively wide outer surfaces, one of said pair of relatively narrow outer surfaces defining a pair of superimposed passageways between said space and the outside thereof;
  - (b) a pair of hollow rivets projecting transversely through said pair of relatively wide outer surfaces of said housing and integrating said pair of shells into a structural unit, each of said pair of hollow rivets defining a cylindrical duct having a sufficiently large inner diameter to allow the passage of screws for supporting said housing through said pair of relatively wide outer surfaces of said housing;
  - (c) a permanent magnet inside said space defined by said housing projecting with one end thereof into one of said pair of passageways and having a pole surface arranged substantially flush with said one of said pair of relatively narrow surfaces of said housing;
  - (d) a fixed armature plate cooperating with said permanent magnet to maintain a door by magnetic attraction in the closed position thereof, said armature plate being arranged substantially parallel to said pole surface of said permanent magnet;
  - (e) a first latch supported by said armature plate at a point juxtaposed to the other of said pair of passageways and projecting from said armature plate in the direction of said other of said pair of passageways;
  - (f) a second latch cooperating with said first latch and arranged inside said space and movable relative to said housing; and
  - (g) electromagnetic means inside said space for operating said second latch.

3. A latching mechanism for doors comprising in combination:
- (a) a housing including a pair of complementary shells defining an enclosed space;
  - (b) a permanent magnet inside of said space having a pole surface arranged substantially flush with one side of said housing;
  - (c) a pivotable latch inside said space having a predetermined fulcrum and being pivotable to two limit positions about said fulcrum, said latch defining a pair of recesses each to one side of said fulcrum;
  - (d) an over-center spring biasing said latch to one of said two limit positions thereof; and
  - (e) an electromagnet inside said space including a pivotable armature having an abutment arranged to alternately engage upon any pivotal motion of said armature one of said pair of recesses defined by said latch to pivot said latch to one of said two limit positions thereof.

4. A latching mechanism for doors comprising in combination:
- (a) a housing including a pair of complementary shells defining a pair of separate enclosed spaces;
  - (b) a permanent magnet inside of one of said pair of spaces having a pole surface arranged substantially flush with one side of said housing;
  - (c) a fixed armature plate cooperating with said per-

- manent magnet arranged substantially parallel to said pole surface thereof;
- (d) a first latch supported by said armature plate and projecting from said armature plate;
  - (e) a second latch inside the other of said pair of spaces arranged to cooperate with said first latch, said second latch having a predetermined fulcrum, being pivotable about said fulcrum to two limit positions and defining a pair of recesses, each to one side of said fulcrum;
  - (f) an over-center spring inside said other of said pair of spaces biasing said pivotable latch to one of said two limit positions thereof; and
  - (g) an electromagnet inside said other of said pair of spaces including a pivotable armature having an abutment arranged to alternately engage one of said pair of recesses defined by said second latch upon any pivotal motion of said armature to pivot said second latch to either one of said two limit positions thereof.
5. A latching mechanism for doors comprising in combination:
- (a) a housing including a pair of complementary shells defining a pair of separate enclosed spaces, said housing having a pair of juxtaposed relatively wide outer surfaces and having a relatively narrow outer surface at right angles to said pair of relatively wide surfaces, said relatively narrow surface defining a pair of superimposed passageways each between one of said pair of enclosed spaces and the outside of said housing;
  - (b) a permanent bar magnet inside of one of said pair of spaces projecting with one end thereof into one of said pair of passageways and having a pole surface arranged substantially flush with said relatively narrow surface of said housing;
  - (c) a latch pivotally mounted inside the other of said pair of spaces and having a predetermined fulcrum, being pivotable about said fulcrum to two limit positions and defining a pair of recesses, each to one side of said fulcrum;
  - (d) an over-center spring inside said other of said pair of spaces biasing said latch to one of said two limit positions thereof;
  - (e) an electromagnet inside said other of said pair of spaces including a pivotable armature having an abutment arranged to alternately engage one of said pair of recesses defined by said latch upon any pivotal motion of said armature to pivot said latch alternately to one of said two limit positions thereof; and
  - (f) a pair of hollow rivets projecting transversely through said juxtaposed surfaces of said housing integrating said pair of shells into a structural unit, each of said pair of hollow rivets defining a cylindrical duct having a sufficiently large inner diameter to allow the passage of a pair of screws for supporting said housing through said juxtaposed surfaces of said housing.
6. A latching mechanism for doors comprising in combination:
- (a) a housing including a pair of complementary shells defining a pair of separate enclosed spaces, said housing having a pair of parallel relatively wide outer surfaces and a relatively narrow outer surface at right angles to said pair of relatively wide outer surfaces, said relatively narrow outer surface defining a pair of superimposed passageways each between one of said pair of enclosed spaces and the outside of said housing;
  - (b) a pair of hollow rivets projecting transversely through said relatively wide surfaces of said housing integrating said pair of shells into a structural unit, each of said pair of hollow rivets defining a cylindrical duct having a sufficiently large inner diameter

- to allow the passage of a pair of screws for supporting said housing through said relatively wide outer surfaces of said housing;
- (c) a permanent bar magnet inside of one of said pair of spaces defined by said housing projecting with one end thereof into one of said pair of passageways and having a pole surface arranged substantially flush with said relatively narrow outer surface of said housing; 5
- (d) a fixed armature plate cooperating with said permanent magnet and being arranged substantially parallel to said pole surface thereof; 10
- (e) a first latch supported by said armature plate at a point juxtaposed to the other of said pair of passageways and projecting from said armature plate in the direction of said other of said pair of passageways; 15
- (f) a second latch cooperating with said fixed latch pivotally mounted inside the other of said pair of spaces and pivotable to two limit positions thereof, 20 said second latch having a predetermined fulcrum and defining a pair of recesses each to one side of said fulcrum;
- (g) an over-center spring inside said other of said pair of spaces biasing said movable latch to one of said two limit positions thereof; and 25
- (h) an electromagnet inside said other of said pair of spaces including a pivotable armature having an abutment arranged to alternately engage one of said pair of recesses defined by said second latch upon any pivotal motion of said armature to pivot said second latch alternately to one of said two limit positions thereof. 30
7. A latching mechanism for doors comprising in combination:
- (a) a housing including a pair of complementary shells and having a pair of relatively wide outer surfaces and having a pair of relatively narrow outer surfaces at right angles to said pair of relatively wide outer surfaces, one of said pair of relatively narrow outer surfaces defining a pair of superimposed passageways between the interior of said housing and the exterior thereof; 35
- (b) a permanent bar magnet inside said housing arranged at substantially the same level as the upper of said pair of passageways and projecting into said upper of said pair of passageways and having a pole surface substantially flush with one of said relatively narrow surfaces of said housing; 40
- 45

- (c) a fixed armature plate cooperating with said bar magnet arranged substantially parallel to said one of said relatively narrow outer surfaces of said housing;
- (d) a first latch supported by said armature plate at substantially the same level as the lower of said pair of passageways and projecting from said armature plate in the direction of said pair of passageways;
- (e) a second latch arranged inside said housing below said bar magnet and cooperating with said first latch, said second latch having a predetermined fulcrum, being pivotable to two limit positions about said fulcrum, and defining a pair of recesses each to one side of said fulcrum;
- (f) an over-center spring inside said housing biasing said second latch to one of said two limit positions thereof; and
- (g) an electromagnet inside said housing, said electromagnet including an energizing winding arranged at a point of said housing more remote from said one of said pair of relatively narrow outer surfaces of said housing than said bar magnet, said electromagnet further including a pivotable armature arranged at a lower level than said energizing winding and having an abutment arranged to alternately engage one of said pair of recesses defined by said second latch upon any pivotal motion of said armature under the action of said energizing winding to pivot said second latch alternately to one of said two limit positions thereof.
